VARIABLE PITCH PROPELLER
ARRANGEMENT

Archibald Graham Forsyth, Cheam, England,
assignor to The Fairey Aviation Company
Limited, Hayes, England

Application November 14, 1942, Serial No. 465,618

1 Claim. (Cl. 170—163)

1

This invention relates to a variable pitch propeller system, and in particular to a variable pitch propeller system employing two sets of propellers for contra-rotation on coaxial shafts.

In my copending application, Serial No. 449,123, filed June 30, 1942, an arrangement of the general type is described in which the pitch of the blades of the propellers of each set may be changed to effect conditions of fine pitch, coarse pitch, feathering and braking, the relative relationship of the pitch of the blades of both sets of propellers, however, remaining the same at all times. In the above-mentioned application, means are illustrated and described for effecting the desired pitch at the will of the pilot as required by flight conditions.

The present invention constitutes an improvement of such means, and primarily resides in providing special means to effect a more rapid adjustment from one pitch condition to another as emergency flight and landing conditions may require.

Another object of the invention resides in the provision of booster means operable at the will of the pilot to assist the power means for effecting a pitch change from one condition to another. The invention contemplates booster means of various types and includes both electrical and hydraulic instrumentalities adapted to accomplish the desired result.

Still a further object resides in an improved control for such booster means as related to the pitch changing system as a whole.

In accordance with the invention, the blades of the two propellers are maintained in a fixed relationship with respect to each other over the entire pitch changing range, the mechanism being so arranged that the pitch of the propellers may be the same or may differ to suit the requirements necessary to obtain maximum efficiency. Further, in accordance with this modification, the propeller shafts can be rotated at any speed relative to each other without upsetting the pitch relationship between the blades of the two propellers. As in my previous application referred to above, means are provided to cover the adjustment in either direction from reverse or braking pitch to fine position, from fine position to coarse position, and from coarse to feathering position.

The invention effects pitch changing movement of the blades about their longitudinal axes through gearing arrangements such as described in my copending application, such gearing being driven by a motor which may be electric or hydraulic. In particular the present invention employs a

2

booster motor to speed the pitch changing movement in either direction from reverse to fine position.

A further object resides in the provision of control means for actuating the booster means at the required periods.

These and other objects of this invention will become more apparent from a consideration of the following specification and claim when read in the light of the accompanying drawings, in which:

Figure 1 is a side elevation, partly in section, showing one form of the invention;

Figure 2 is a cross-sectional view taken on line 15 2—2 of Figure 1;

Figure 3 is a view partly in elevation and partly in cross-section taken on the line 3—3 of Figure 1;

Figure 4 shows a modification of the invention partly in cross-section and partly in elevation;

Figure 5 shows a still further modification in side elevation and partly in cross-section;

Figure 6 shows in section a preferred form of a hydraulic system adapted to vary the propeller pitch;

Figure 7 is an end elevation on the line 7—7 of Figure 6;

Figure 8 is a cross-sectional view taken on the line 8—8 of Figure 6;

Figure 9 is a diagrammatic representation showing an electrical circuit arrangement used in carrying out this invention;

Figure 10 illustrates a modification of a hydraulic system adapted to vary the pitch of a propeller blade;

Figure 11 is a further modification of the arrangement shown in Figure 10;

Figure 12 illustrates a modification of the booster motor arrangement;

Figure 13 illustrates a modified type of clutch adapted to be used in this invention;

Figure 14 is a cross-sectional view taken on the line 14—14 of Figure 13.

In considering this specification and the accompanying drawings, attention is directed to my Patent No. 2,161,917 and my pending application, Serial No. 449,123, filed June 30, 1942.

Referring now more specifically to Figures 1, 2 and 3 of the drawings, the reference numerals 50 2 and 4 indicate two propellers mounted respectively on two coaxially disposed hollow drive shafts 6 and 8, each of which are adapted to be rotatively driven by internal combustion engines (not shown) with each engine having its own controls. Obviously, with such an arrangement

it becomes possible to operate the engines at any desired speeds relative to each other, or to stop one engine while permitting the other to operate.

In this embodiment of the invention, the roots of the propeller blades (in this case three on each shaft) are each mounted for rotary movement about its longitudinal axis so that the pitch of the blade can be adjusted over a range of 360°. To accomplish this movement, the root of each propeller blade 2, 4, is rigidly secured to ring gear 10, which is engaged by a worm gear 12, 12' rigidly secured on the shaft 14, 14'. As these gears are turned in one direction or the other by means to be described, the worm gears 12, 12' will rotate the ring gears 10 which, since the gears are rigidly mounted on the propeller blade roots, will rotate the blades about their respective longitudinal axes, thus changing the pitch of the blades.

In the present invention the propeller pitch changing means for the blades 2 comprises a reversible electric motor 16 which is provided with a drive shaft 18 on which is rigidly secured coaxially therewith the gearwheel 20 which coacts with the gear 22 (coaxial with respect to the propeller drive shafts). As is clearly seen in Figure 1, the gear 22 is provided with a laterally extending flange portion 24 having gear teeth cut on the outer periphery thereof. A spider 26 carries the coaxially mounted gears 28 and 30, of which gear 28 is adapted to be engaged by the gear teeth formed on the flange 24 and to be rotated thereby. A ring gear 32 has gear teeth formed on its inner periphery which are also engaged by the gear 28 mounted on the spider 26. A gear 34 keyed to the frame 36 is adapted to mesh with the spider mounted gear 28. The gear 28 also meshes with a second ring gear 38 which is rigidly secured to the propeller hub. The ring gear 32 is provided with gear teeth cut on its exterior periphery which mesh with and rotate gear 40 under certain conditions to be discussed below. The gear 40 is rigidly mounted on the shaft 14, which, it will be recalled, has also fixedly secured thereon, the worm gear 12.

It is now seen that when the reversible electric motor 16 is energized to rotate in one direction, the gear 20, driven by the shaft 18, will rotate the gear 22 which in turn transmits its rotation through the gear 28 to the ring gear 32. The rotation of gear 32 will turn gear 40 which, since it is mounted rigidly on shaft 14, turns the worm gear 12. The worm gear 12 cooperates with the ring gear 10 to rotate the propeller blade 2 with respect to its longitudinal axis thereby changing the pitch thereof.

The other end of the shaft 14 is provided with a second gear 42 fixedly mounted thereon. This gear, when rotated transmits power through a gearing system identical to that previously described in order to vary the pitch of propeller blade 4. The various elements found in the second gear train may be identified by the primed reference numerals indicating similar elements to be found in the first system.

One of the objects of this invention is to provide means whereby the rate of change of pitch may be rapidly accomplished. This is achieved by selecting a high gear ratio with respect to gears 28 and 32. In addition thereto, it has been found advantageous to employ a booster motor 42 of approximately the same power as motor 16. Motor 42 is employed when it is desired to change the pitch from fine to breaking (and the reverse thereof), and its cooperation with the gearing system is readily understood.

The gear wheel 22 engages the freely rotating gear 44 rigidly mounted on one end of a shaft 46. The other end of the shaft carries the female portion or clutch plate 48 also rigidly secured thereon. The male portion 50 of the clutch is telescopically mounted on and is keyed to the drive shaft 52 of the electric motor 42. A pivoted link 54 is secured at one of its ends to the telescoping member 50. The other end of the link 54 is secured to the shaft 56 which is operable by the energization of the electric solenoid 58. The solenoid 58 and the motor 42 are controlled through an electric circuit to be described.

In Figure 5 a modification of the invention is illustrated. In this figure the inner gearing system adapted to vary the pitch of the propeller blade 2 is identical to the gearing systems described in connection with Figure 1, and identical reference numerals are employed to identify the same elements. However, in this modification, the gear wheel 42 engages the ring gear 60 which is provided with gear teeth on its outer periphery for this purpose. The inner periphery of the ring gear 60 is provided with gear teeth which are engaged by a gear 62 mounted coaxially with gear 64 on the spider 66. The gear 64 meshes with gear teeth formed on the inner periphery of the ring gear 68 and also cooperates with the gear 70 which is keyed to the shaft 8. As is seen in the drawing, the gear 62 also meshes with the gear 72 which is substantially U-shaped in cross section. This gear engages the gear 45 which when rotated, will turn the worm gear 12, thereby varying the pitch of the propeller blade 4.

In Figure 4, another embodiment of the invention is illustrated. In this modification the shaft 18 drives the gear 22. The gear 22 is engaged by gear 28 mounted coaxially with gear 30 and is carried by the spider 26. The gear 28 engages teeth formed on the inner periphery of the ring gear 74 which is rigidly secured to the propeller hub. The inner ring gear 76 is provided with radially inwardly extending gear teeth which engage gear 30.

Gear 30 cooperates with gear 78 which is keyed to the frame 36. It will also be seen that the gear 76 cooperates with the gear 80 which is rigidly secured to the shaft 14. Hence, it is easily seen that energization of the motor 16 will turn gear 80 which rotates the propeller blade in the manner described above.

The variable pitch gear mechanism is controlled through the equipment and electrical circuit diagrammatically shown in Figure 9. In considering this figure it will be seen that a portion thereof is quite similar to the electrical circuit shown and described in my copending application, Serial Number 449,123.

Included in the circuit shown is a battery 200 for supplying current to the electric motors 16 and 42, solenoid switches 202, 204, 206, and 208, manually operated feathering switch 210, a double switch 212, 212' operated by the governor 214 which is geared to a shaft 215 driven by the internal combustion engine, a manually operated switch 216 for overriding the governor at the will of the operator, a braking switch 218 and a series of limit switches 220, 222, 224, 226, 227 and 228. The limit switches are controlled by a number of cam shaped disks 220', 222', 224', 226', 227' and 228' adjustably mounted on the shaft 230 which is connected with the motor 16 through reduction gearing (not shown).

In Figure 9, the normal circuit is indicated in full lines, the feathering circuit in dotted lines, while the hand control circuit for overriding the

governor is indicated in dot and dash lines. The fine pitch switch 222 and the coarse pitch switch 224 are both located in the normal circuit. The cams 222' and 224' are so positioned on the shaft 230 so as to permit the switches 222 and 224 to be held in their closed position during normal operation. In normal operation of this circuit the tension of the spring 230 is adjusted to regulate the governor 214 to suit the R. P. M. of the engine decided upon by the pilot for operation. The governor when operating thus actuates the pivoted switch lever 232 so that it will either close the fine pitch switch 212 or the coarse pitch switch 212'. In accordance with the particular switch actuated the electric motor 16 will rotate the shaft 230 so as to tend to bring the cams 222', 224' into contact with their respective switch arms. If the cams are rotated far enough one or the other of the cams 222', 224' will actuate either the fine pitch limit switch 222 or the coarse pitch limit switch 224, thus breaking the normal circuit and cutting off the motor.

The fine pitch limit switch 222 and the coarse pitch limit switch control the predetermined coarse and fine positions of the propeller blade pitch. For example, the fine pitch limit switch 222 only comes into operation during take off and feathering, and the coarse pitch limit switch 224 acts to prevent over pitching in a dive. In normal flight neither switch is actuated by their respective cams.

In this arrangement when the engine is stopped the governor weights 234 move in such a manner as to close the "fine" switch 212 (the "coarse" switch 212' can only be closed when the engine is operating). Thus the electric motor 16 is placed under operation and will rotate the cam shaft 230 until the cam 222' operates the switch 222 thereby breaking the motor circuit. This insures that the blades will always be left in fine pitch for a take off.

Should it become necessary for any reason to "over-ride" the governor, the pilot may accomplish this by manually actuating the hand control switch 216 which is in the circuit indicated by dot and dash lines. Consequently, if this switch be actuated to cut out the governor, the electric motor 16 will be actuated to rotate the cam shaft 230 so as to tend to cause the cams 222' or 224' to operate their respective switches. The circuit to the motor is, of course, broken either by operating the hand control 216 or by the opening of either of the two switches 222, 224.

When it is desired to feather the propellers, it is necessary for the pilot to actuate the feathering switch 210 so that the normal circuit (full line) is broken and the feathering circuit indicated in dotted lines, is made. As is seen, during normal operation no current passes through this circuit.

Operation of the feathering switch to close the feathering circuit permits current to pass through the contacts of the feathering limit switch 226 and at the same time since the normal circuit is dead, the coarse pitch limit switch 224 will be dead so that actuation of this switch by the cam 224' will not operate to shut off the current to the motor 16. As the shaft 230 continues to rotate, the cam 226' will operate the feathering limit pitch switch 226 thereby opening the feathering circuit, stopping the electric motor 16 and holding the propeller blades in feathered position.

When the feathering limit switch 226 is broken, the fine pitch limit switch 222 circuit is still alive, and due to the fact that the governor has moved the pivoted switch into fine position; the electric

motor 16 is reversed and automatically rotates the shaft 230 to bring the cams 222' and 224' back into position to actuate their respective limit switches 222, 224.

5 It is also obvious that actuation of the hand control switch 216 in the hand control circuit (broken line) may be used to bring the propeller blades back to normal position. It is necessary, of course, to return the feathering switch 210 to the position shown in Figure 9 to break the feathering circuit and close the normal running circuit.

10 Attention is called to the fact that with the hand control switch it is not only possible to over-ride the governor, but to change the pitch of the propellers at will and to leave the blades set in the best possible position for economical cruising. For example, the blades may be feathered by operation of the switch 216 provided feathering switch 210 is put into feathering position.

15 Moving the switch 216 in a counter-clockwise direction from the position shown to the first set of terminals will cut out the governor and complete the fine pitch circuit. Moving it clockwise to the first set of terminals will close the coarse pitch circuit.

20 Continuing in the same direction to a position at right angles to the first position will effect an "off" position in which the blades are locked. This switch obviously may be rotated as much as 360° in either direction. It will be

25 apparent that usually this switch 216 will remain in a normal running position in which the governor is in actuation, but can be used, for example, on long cruises and the like, so that the pilot can set the pitch in the best possible position for the most economical operation.

30 As was stated above, one of the objects of this invention was to provide means for changing the pitch of the propeller blades rapidly from the fine pitch position to breaking pitch position and reverse. To accomplish this feature of the invention, the booster motor 42 is brought into operation and simultaneously one or the other of the electric solenoids 206, 208 is energized to bring the clutch into engagement to add the power of 35 the motor 42 to that of motor 16.

35 The braking limit switch 210 during normal operation is dead since the normal circuit bridges it, but when it is desired to effect the braking position after the aircraft is on the ground, it

40 may be rendered live by braking switch 218 interconnected with the brake pedal or lever (not shown). In construction this switch may be similar to that of the feathering switch 210, but in addition includes two terminals 236 and 238. In

45 inner terminal 238 of the braking switch 218 is connected to the magneto ground terminals (not shown) while inner terminal 236 is connected to one side of the normally open switch 240, the other side of which is connected to the ground.

50 The switch 240 is adapted to be closed by operation of a pin 242 when the latter is raised by the

55 pivoted arm 232 controlled by the governor 214.

55 In the normal position of switch 218, the switch connects a pair of terminals, one of which 244 leads to the "coarse" switch 212' and the other 246 to the "fine" switch 212. This latter terminal 246 is also connected in the hand control circuit by line 248 so that when switch 218 is in normal position, the hand control switch 216 may still be actuated to override the governor.

60 In practice, the braking switch 218 is adapted to be operated by the foot brake pedal when the plane lands. As the pilot applies the brakes the switch 218 is turned from the position shown to 65 its other position. This takes the current directly

to the braking limit switch 220, through the solenoid 204 and back to the other terminal of the battery, even though the cam 222' actuates and opens the fine limit switch 222. The solenoid 208 is energized simultaneously therewith and the armature thereof operates to close the motor switch 250 thereby energizing the motor 42 and also operates the linkage system to close the clutch thereby adding the power of the motor 42 to that of the motor 16. Motors 16 and 42 continue to operate until limit switches 220 and 228 are opened by the rotation of the cams 220' and 228'. Turning the hand switch 218 to coarse position and releasing the brake pedal the switch 218 is moved back to its normal position and establishes an electrical circuit through solenoids 202 and 206 which reverses the direction of the rotation of the motors, and maintains the clutch in engagement with the motor 42. The shaft 230 continues to rotate until the switch 227 operated by the cam 227' is opened simultaneously with the opening of limit switch 224, thereby opening the circuits through all motors and solenoids. The cams 227' and 228' normally hold the switches 227 and 228 in open position, allowing them to become active only during the braking operation.

In "off" position switch 218 completes the negative for the coarse pitch circuit (either governor or hand controlled) thereby making it possible to go into reverse pitch when reverse pitch is required (when plane is on the ground and a foot pedal braking is applied to place switch 218 in "on" position) even when the pilot controls are in coarse pitch position. Inner terminals 236 and 238 complete the ignition switch wires and complete the circuit through the governor actuated switch 240 to ground when switch 218 is in "on" position. Switch 240 is normally open and can only be actuated to close the circuit when switch 218 is "on." The switch 240 is designed to break only when going into a reverse pitch position and only when a predetermined lower limit of R. P. M. is reached.

This arrangement constitutes a safety measure since braking a reverse pitch position of the propeller cannot be effected until the aircraft is on the ground and the pilot has applied the foot pedal and the motor has slowed down to a predetermined R. P. M.

Hence, it is seen that a rapid change from fine pitch to reverse pitch and the reverse is effected through the introduction of the power derived from motor 42.

In Figure 6 a hydraulic system adapted to vary the pitch of the propellers through the gearing arrangement described above is illustrated.

This embodiment employs a cylinder 82 which is provided with coaxial threaded apertures 84 in the respective ends thereof. A piston 86 is rigidly and coaxially mounted on the shaft 88 which is in turn mounted in the apertures 84 to permit reciprocal movement of the piston 86 in the cylinder 82. Threaded sealing rings 90 engage the threaded apertures and are adapted to hold packing 92 securely in place. A gear rack 94 is rigidly secured to the ends of the shaft 88 by means of the supports 95. Adjacent each end of the cylinder 82 two openings 96 and 98, respectively, are provided. One end of each of the pipes 100 and 102 is fixedly mounted therein and each end is packed (not shown) against leakage. A suitable reversible hydraulic pump 102' is connected to the other ends. Consequently, operation of the hydraulic pump 102' in one di-

rection will furnish fluid through one of the conduits 100, 102 and will provide a suction on the other; reversing the pump will reverse the function of the conduit pipes. Pump 102' may be controlled in any well known manner such as manually or by a governor operating in response to the rotational speed of the engine and propeller.

It is to be understood that fluid entering one end of the cylinder 82 under pressure will force the piston 86 toward the opposite end and vice versa. In moving from one end of the cylinder to the other, the fluid pressure acting on the piston 86 causes a longitudinal movement of the gear rack 94. As is seen in Figures 6, 7 and 8, the upper surface 104 of the gear rack is substantially planar and cooperates with a similar surface on the bottom or base of the cylinder 82. These cooperating surfaces prevent any rotation of the rack about the shaft 88.

The rack 94 engages the gear wheel 22 and as the fluid under pressure is admitted alternately to one or the other surfaces of the piston 86, the gear 22 is rotated first in one direction and then the other which results in a change of the propeller blade pitch as explained above.

In the event a more rapid change of pitch is required, a booster pump and circuit is provided, the control thereof being positioned in the cockpit or is adapted to be operated by the brake pedal. The booster circuit comprises a hydraulic pump 106 connected to a source of fluid supply (not shown) and is connected to the interior of the cylinder through conduits 108, 108'. The high pressure side of the conduit is, at the will of the operator, alternately connected with the interior of the cylinder at opposite ends thereof by adjusting valve 114. Whichever of conduits 108, 108' is not connected to the high pressure side of pump 106 is connected to the fluid reservoir (not shown). A suitable by-pass circuit is connected with the high and low pressure sides of the conduit 108 to prevent the fluid pressure from building up behind the valve 114 when it is in closed position. This circuit comprises the pipe 110 and the spring tensioned valve device 112.

It will be noted that the booster arrangement just described operates completely independently of the pitch varying arrangement which includes conduits 100, 102. This has the advantage of not only permitting accelerated pitch changing movement of the blades when desired, but also provides a safety factor in that a defect or breakage in one of the hydraulic fluid supply systems will not leave the pilot without means for changing the propeller pitch. In systems wherein booster arrangements operate through one or more common parts, such as a valve, with the ordinary pitch control arrangement, a defect in the common part would disable both control systems.

Figure 10 illustrates a modification of the hydraulic system which may be employed in effecting the rapid change of pitch, from fine to braking and the reverse thereof. This figure also shows a method for changing the pitch of the propeller blades through their normal phases of fine pitch, coarse pitch and feathering.

In this construction, the cylinder 82', piston (not shown), gear rack 94', supports 95', threaded apertures 84' and threaded sealing rings 90' are identical to the corresponding elements shown in Figures 6, 7 and 8. This embodiment employs but two conduits 300 and 302, one end of each of the conduits communicating with the interior of the

cylinder 82' at a point adjacent each of its ends. The other ends of the conduits are connected with a valve device 304 which is controlled by the governor 306 connected to the internal combustion engine.

A shaft 308 is mounted for reciprocal movement within the cylinder 310, the degree of movement being dependent upon the speed of the engine. Rigidly secured on the shaft 308 are the valve pistons 312, 312'.

The intake port of the hydraulic pump 314 is connected to a source (container) of fluid supply 316 through conduit 318. The high pressure side of the pump 314 is connected with a chamber 320 through pipe 322. The chamber in turn is connected with the interior of the valve 304 through the conduit 322.

The container 316 is also connected to the cylinder 310 adjacent each end thereof by discharge conduits 324 and 326.

During normal operation of the internal combustion engine, the governor will reciprocate the shaft 308 and, of course, the valve pistons 312, 312', thereby connecting the conduits 300 and 302 with either the high pressure pipe 322 or with one of the discharge pipes 324 or 326. The change in pressure on one side or the other of the piston in the cylinder 82' will produce a movement of the gear rack 94' which is transmitted to the gear wheel 22' which rotates the propeller blades to effect a change of pitch.

In the event it is desired to move from normal running pitch to braking pitch, a booster pump 328 is provided. Pump 328 is energized by closing switch 330 which may be connected with the brake pedal. The low pressure side of the pump 328 is connected by pipe 332 to the fluid supply and the high pressure side is connected with the chamber 320 through pipe 334. A one-way valve 336 is introduced in conduit 334 intermediate the chamber 320 and the pump 328 to prevent the fluid from passing to the pump 328 when the device is working under normal conditions. It now becomes obvious that when the pump 328 is operated, the fluid pressure on one or the other sides of the piston in cylinder 82' will be increased, thereby actuating the gear rack 94' at a much higher speed. This will, of course, change the pitch of the propeller blades very quickly. A pressure by-pass circuit comprising the valve 338 and the conduits 340, 342 is also provided, the function of which is well understood.

In Figure 11 a still further modification of the hydraulic system is illustrated. In this system, the gear 22', cylinder 82', gear rack 94', conduits 300' and 302', discharge pipes 324 and 326, pumps 314' and 328', valve device 304' and the governor 306' are identical in construction to similar elements shown in Figure 10. In this embodiment, however, the high pressure side of the pump 314' is connected directly with the governor operated valve device 304' through conduit 344. The low pressure side of the pump is connected to the fluid supply through pipe 346, the three-way valve 348 and the pipe 350. The booster pump 328' is connected at its high pressure side, with the valve 348 by the pipe 352, and the low pressure side is connected with the fluid supply through conduit 350'. (A bypassing circuit is also provided for the booster pump 328' comprising the valve 338' and conduits 340', 342'.)

During normal operation only the pump 314' is employed to adjust the pitch of the propeller blades. In this case the valve 348 is connected directly with the valve device 304', and the fluid

supply through pipe 346, as shown. When, however, it is desired to obtain a rapid change of pitch, the switch 330' is closed thereby starting the booster pump 328' and simultaneously therewith the three-way valve 348 is turned to connect the high pressure side of the booster pump 328 with the low pressure side of pump 314'. This results in increasing the pressure in the high pressure pipe 344 which in turn will increase the pressure on one or the other sides of the piston in the cylinder 82' and will effect a more rapid change in pitch in the manner described above.

When braking pitch is no longer required, the switch 330' and valve 348 are returned to their original positions thereby cutting off the booster pump motor and connecting the low pressure side of pump 314' with only the fluid supply.

Figure 12 illustrates a modification of the arrangement of the normal pitch changing motor 16 and booster motor 42. In this illustration the booster motor 42 is adapted to transmit its power (when required) directly to the shaft 14 when the motor 42 is energized and the clutch elements 48 and 50 are brought into engagement in the manner described. It will be seen in this figure that the driving shafts of each motor are coaxial and oppositely disposed.

Figure 13 illustrates a modification of the clutching mechanism for the booster motor. In this figure, the motor 42 is energized and simultaneously therewith the electro-magnets 400 mounted on the drive shaft 18 are also energized to cause the clutch plate 402 to engage the female clutch portion 404 which is rigidly secured to the drive shaft 18.

Having described my invention in detail, it is to be understood that the invention is not to be limited to the specific examples described and illustrated herein, but is only limited by the scope of the following claim:

I claim:
In an airplane propeller pitch changing mechanism, a hydraulic cylinder; a piston in said cylinder; a rack and pinion arrangement drivably connecting said piston with the propeller blades; a first pitch control arrangement comprising a reversible hydraulic pump connected to supply fluid under pressure selectively to either side of said piston; and a booster pitch control operable simultaneously with said first pitch control for causing accelerated pitch changing movement of said blades, said booster control being operable entirely independently of said first pitch control and being connected to said cylinder entirely independently of said first pitch control, said booster arrangement comprising a second hydraulic pump, and a valve for selectively connecting the output of the second pump with either end of said cylinder entirely independently of the supplying of fluid to said cylinder by the pump of said first pitch control arrangement.

ARCHIBALD GRAHAM FORSYTH.
